UNITED STATES PATENT OFFICE

GEORGE T. HORTON, OF CHICAGO, ILLINOIS, ASSIGNOR TO CHICAGO BRIDGE AND IRON COMPANY, OF CHICAGO, ILLINOIS, A CORPORATION OF ILLINOIS

HANGER FOR FLOATING ROOFS

Application filed January 12, 1931. Serial No. 508,279.

This invention relates to improvements in hangers for floating roofs and, more especially, a hanger adapted for the temporary support of such a floating roof adapted for use in liquid storage tanks.

In the storage of gasoline, hydrocarbon oils, and other volatile liquids, it is customary to employ a floating roof that floats on the surface of the liquid in the tank in order 10 to eliminate or lessen evaporation losses.

In such tanks, it is frequently necessary or desirable to empty the tank of liquid for cleaning purposes, and the like, and in such cases, it is highly desirable to support the 15 roof a sufficient distance above the bottom of the tank to permit the entry of workmen thereunder. In the normal operation of the roof, however, it is desirable that the roof descend to a lower point than fixed by such 20 temporary support.

My improved hanger is adapted for use as a temporary support for the purposes above described and the same will now be discussed more in detail.

25 Other features and advantages of my invention will appear more fully as I proceed with my specification.

In that form of device embodying the features of my invention shown in the accompanying drawing—

Figure 1 is a view in side elevation; Fig. 2 is a view similar to Fig. 1 on an enlarged scale showing the hanger; and Figs. 3 and 4 are views in perspective of parts of the apparatus.

As shown in the drawing, the tank is here indicated as comprising a cylindrical shell 10 with a bottom 11. The shell, as here shown, is made with overlapping plates 10^a, 10^b and the like, fastened together by rivets 10^c. This is an ordinary form of tank construction.

The floating roof is represented by 12 and includes the circular supporting pontoon 45 12^a with the central sheet metal portion 12^b. A floating roof of this kind is ordinarily made of somewhat smaller diameter than the diameter of the tank so that it will move freely upwardly and downwardly. This leaves an annular space 13 between the

periphery of the roof and the wall of the tank. Suitable means are ordinarily provided for sealing this space. The details of such sealing means form no part of the present invention. Such sealing means, however, ordinarily includes a plurality of shoes 14 or other members adapted to bear against the inner wall of the tank. For convenience, these shoes are here shown as supported by hangers 15 and 16 indicates a 60 flexible fabric strip sealing the space between the shoes and the periphery of the floating roof.

Any sealing means having members such as the shoes 14 or equivalent means adapted to slide along the inner wall of the tank usually has such members provided with inwardly bent beveled or curved edges, as indicated by 14^a, to permit the same to ride over unevennesses on the inner wall of the tank, 70 such as, for example, the edges of overlapping plates 10^b and the heads 10^d of rivets 10^c.

My improved hanger includes a plurality, for example, four or more, relatively thin 75 plates 17 attached to the inner wall of the tank 10 by welding or otherwise. These plates, as shown in Fig. 3, have a portion cut out, as indicated by 17^a, for the reception of the hooks 18, shown in Fig. 4.

There is provided a hook for each of the plates 17, and these hooks are attached to the periphery of the deck 12 by the flexible members or chains 19. When the hangers are not in use, the hooks are removed from the sockets 85 and carried on the floating deck.

The sockets 17 are preferably thin enough so that the shoes 14 or other members used in connection with the sealing apparatus will ride over the same, for example, such socket pieces 17 may not be substantially thicker than the thickness of the plates 10^b plus one of the rivet heads 10^d. If the plates 17 are no thicker than this, the sealing members 14 will ride over the same just as easily as they will ride over the joints made by the overlapping plates in the tank construction. It is to be noted that the plates 17 are relatively thin, but that they may be made wide enough and long enough to give the desired strength. 100

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

What I regard as new, and desire to secure by Letters Patent, is:

1. In combination with a tank and a floating roof therefor having sealing means including parts adapted to slide vertically along the inner wall of the tank, a hanger for said roof including relatively thin wide socket members fastened to the inner wall of the tank and hooks flexibly attached to the floating roof adapted for engagement with the said socket members, said socket members being thin enough so that the aforementioned parts of the sealing means adapted to slide along the inner wall of the tank will slide over said socket members without substantially impeding the vertical movements of the floating roof.
2. In combination with a tank formed of overlapping plates and a floating roof therefor, a hanger in said floating roof including a relatively thin wide socket member attached to the inner wall of the tank, said socket member being not substantially thicker than the thickness of the overlapping plates of which the tank is constructed, and a hook flexibly attached to the floating roof, said hook adapted for engagement with said socket member.

In witness whereof, I have hereunto set my hand and seal, this 9th day of January, 1931.

40 GEORGE T. HORTON.
